Specification for Design.

Patented Dec. 6, 1921.

Application filed April 21, 1920. Serial No. 375,637. Term of patent 14 years.

To all whom it may concern:

Be it known that I, ARTHUR V. GULLBORG, a citizen of the United States, residing at Chicago, in the county of Cook and State of Illinois, have invented a new, original, and ornamental Design for a Lubricator-Nipple, of which the following is a specification, reference being had to the accompanying drawing, forming part thereof.

In the drawing,

Figure 1 is a plan view.

Fig. 2 is a side elevation; and

Fig. 3 is a side elevation taken at an angle of 90° to view in Fig. 2.

I claim:

The ornamental design for a lubricator nipple as shown.

In witness whereof, I hereunto subscribe my name this 9 day of March, 1920.

ARTHUR V. GULLBORG.
